JAMES F. GORDON, OF LOWELL, MASSACHUSETTS.

PILE-WIRE.

1,125,410.

Specification of Letters Patent.

Patented Jan. 19, 1915.

Application filed June 17, 1912. Serial No. 704,221.

To all whom it may concern:

Be it known that I, ROYAL A. STEVENS, a citizen of the United States, residing at Lowell, in the county of Middlesex and 5 Commonwealth of Massachusetts, have invented a certain new and useful Improvement in Pile-Wires, of which the following is a specification.

This invention relates to pile-wires, such 10 as are used in looms for making pile fabrics, the wires sometimes forming the loops or pile which project from the face of the fabric as in uncut velvet or Brussels carpet and sometimes being provided with 15 knives which cut through the tops of the loops when the wires are withdrawn from them, as in making cut velvet or Wilton carpets. In either case the pile-wire comprises a head of thin or sheet metal and a flat 20 tempered steel wire, one end of which is laid in a groove or slot in said head and secured to said head, more commonly by brazing, destroying the temper of the wire and rendering it liable in use to be broken 25 at the head, after which both the head and the wire are practically useless. Sometimes the wire is secured to the head wholly or partly by solder, sometimes by means of rivets or clamps and rivets. There is a 30 great strain on the wire when it is being drawn from the loops of the fabric and if the wire proper or blade is broken or separated from the head, as frequently happens, the device must be taken to the repair shop 35 if capable of being repaired or if not, must be thrown away.

The object of this invention is to furnish a means of securing the head and wire proper or blade to each other, such that said 40 wire or blade may be tempered uniformly throughout in such a manner as to prevent bending of the blade and almost entirely obviate the danger of breaking it and at the same time to enable the loom-fixer to substitute a new head, wire or blade for the broken one in the weaving-room, immediately, thereby lessening the loss of time and cost of 45 repairs.

In the accompanying drawing, Figure 1 50 is a side elevation of a pile-wire head and the adjacent part of a dovetail wire held in a dovetail groove in said head by a segmental disk lock. Fig. 2, a vertical cross-sec-

tion on the line 2 2 in Fig. 1; Fig. 3, like Fig. 2, except that the lock is represented as provided with a projection which may be turned to engage a notch in the wire or out of engagement therewith; Fig. 4, a vertical cross-section on the line 4 4 in Fig. 3; Fig. 5, a side elevation of a modification,—in which two rotary locks are used with a wire rectangular in cross-section, except at the points engaged by the lock, Fig. 6, a vertical cross-section on the line 6 6 in Fig. 5.

In Fig. 1 the head A of the pile-wire is 65 of the usual construction, except as herein-after stated and is provided with a dovetail groove *a* which receives and fits a dovetail shank *b* of the wire B, the end of the wire farthest from the head A being of any 70 usual shape, that is, either with or without a pile-cutting edge, said free end not being shown, as my invention relates merely to securing the wire in the head. In Fig. 1 a hole *a*¹ circular in cross-section and with 75 enlarged or flaring ends is punched or otherwise formed in the head and partly within the groove which receives the pile-wire and a plug C circular in cross-section is arranged in said hole *a*¹ the ends of the plug 80 being spread to fit the flaring ends of the hole and retain said plug therein with considerable friction, in order that the plug may not be easily jarred or turned out of position. The plug is provided with a central hole *c* to receive a key or may be slotted across the top, as shown at *c*¹ in Fig. 3 to be engaged by a screw-driver. The top of one side of the plug C is cut away to the bottom of the groove *a*¹ sufficiently to allow 90 the wire to be inserted and drawn out of the head when the plug is turned to bring this cut portion parallel with said groove. The wire on the side next the plug or lock C is provided with a concave recess *b*¹ which 95 fits the curved surface of said plug or lock, so that when said lock is turned into said recess the wire cannot be drawn out of the head. At the inner end of the groove *a* which receives the pile-wire is a hole *a*² 100 having a diameter as great as the greatest width of said groove, for the purpose of clearance in forming the groove and when the pile-wire is locked in the groove, the inner end of said pile-wire may extend entirely across this opening, as shown in Fig. 105

1. The ends of the lock in Fig. 1 as in all the other figures do not extend beyond the adjacent surfaces of the head.
- 5 In Fig. 3 the lock C^1 differs from that shown in Fig. 1 in being provided with a projection c^3 beyond the curvature of the disk, which projection may be turned to engage a lateral depression b^2 in the wire, as shown to prevent the wire from being drawn out of the groove a or may be turned up into another depression or recess a^3 in the head at the side of the groove to allow the wire to be drawn from said groove. In other respects the devices shown in Figs. 15 3 and 4 are like those previously described and indicated by the same letters of reference, it being understood, of course, that the circular hole in Fig. 3 which receives the plug is wholly outside of the groove.
- 20 In Figs. 5 and 6 the holes a^4 a^4 which receive the locks are partly within the groove which receives the wire, there being two such locks, one above and the other below said wire and the wire B and said groove being rectangular in cross-section, said wire being provided at the open side of the groove with concave recesses b^3 b^3 which do not however extend through the entire thickness of the wire and the locks 25 being provided with enlarged flanges which enter said recesses b^3 b^3 which thus not only prevent a vertical movement of the wire, 30

but also hold the wire in the groove by overlapping the bottom portion of these concave recesses.

35

I claim as my invention:

1. The combination of a pile-wire head provided with a longitudinal groove and with a hole, a wire arranged in said groove and provided with a recess and a lock capable of turning in said hole, to engage said recess and to retain said wire in said groove or to release said wire.

2. The combination of a pile-wire head provided with a longitudinal groove and with a hole, a wire arranged in said groove and provided with a recess and a lock capable of turning in said hole to engage said recess to prevent a longitudinal movement of said wire in said groove.

45

3. The combination of a pile-wire head provided with a groove and with a hole, and a wire having a flat end portion arranged in said groove and having a recess, and being narrower on its outer face than at the bottom of said groove, and a lock turning in said hole to engage said recess to prevent displacement of said wire.

50

In witness whereof, I have affixed my signature in presence of two witnesses.

ROYAL A. STEVENS.

Witnesses:

ALBERT M. MOORE,
WILLIAM F. CURTIN.
